UNITED STATES PATENT OFFICE.

MAZEL L. PORTER, OF ROCHESTER, NEW YORK.

TATTING-SHUTTLE.

1,314,209.

Specification of Letters Patent. Patented Aug. 26, 1919.

Application filed July 3, 1918. Serial No. 243,196.

To all whom it may concern:

Be it known that I, MAZEL L. PORTER, a citizen of the United States, residing at Rochester, in the county of Monroe and 5 State of New York, have invented certain new and useful Improvements in Tatting-Shuttles, of which the following is a specification.

This invention relates to shuttles and 10 more particularly to tatting shuttles.

The main object of the invention is to provide a shuttle of this character having a point always ready and handy for use in joining the rings of tatting and for loosening 15 knots and which does not hinder at all the progress of the tatting.

Another object is to provide a shuttle of this character with the end of one side extending longitudinally beyond the end of 20 the other side and tapered to form a slender point, said point being slightly curved outward.

Another object is to provide a tatting shuttle equipped with means to prevent the 25 thread from pulling out too quickly when the shuttle has been nearly emptied.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made 35 within the scope of what is claimed without departing from the spirit of the invention.

In the accompanying drawings:—

Figure 1 represents a top plan view of a shuttle constructed in accordance with this 40 invention,

Fig. 2 is a side elevation or edge view thereof,

Fig. 3 is a longitudinal section taken on the line 3—3 of Fig. 2, and

Fig. 4 is a transverse section taken on the line 4—4 of Fig. 2.

In the embodiment illustrated, a mounting block 1 is shown around which a thread is wound and secured to the block by means 50 of slits 2 formed on opposite ends thereof which prevent the quick pulling out of the

thread when the shuttle has been nearly emptied.

Secured to the sides of the block 1 in any suitable manner preferably by riveting, are 55 the side plates 3 and 4 pointed at opposite ends in the customary manner to facilitate the passage of the shuttle through the loops of the lace. These side plates 3 and 4 may be composed of celluloid, resilient metal, or 60 any suitable material and one of them has one end extended longitudinally beyond the adjacent end of the other plate and tapered to form a slender point 5 which is curved slightly outward as is shown clearly in Fig. 65 2. This point 5 is designed for loosening knots and for joining the rings of the tatting and by its construction it does not in any way interfere with the process of tatting.

In winding the thread on the mounting block 1, the inner end is first inserted in one of the slits at opposite ends of said block and securely holds the thread so that when the shuttle is nearly emptied, the thread will not 70 75 pull out too quickly.

The side plates 3 and 4 are formed so that they touch each other at their opposite ends, but being of light material such as celluloid that springs apart to permit the thread to 80 pass between them when the shuttle is being wound and when it is used for tatting.

By so constructing this shuttle, it will be extremely inexpensive to manufacture and yet be capable of all the uses for which the 85 more expensive shuttles are adapted.

The foregoing description and the drawings have reference to what may be considered the preferred or approved form of my invention. It is to be understood that I 90 may make such changes in construction and arrangement and combination of parts, materials, dimensions, etc., as may prove expedient and fall within the scope of the claimed invention.

Having thus fully described my invention, what I claim as new and desire to secure by Letters Patent, is:—

A tatting shuttle comprising a mounting block, side plates carried by said block, one 100 of said plates having an integral extension at one end projecting longitudinally beyond

the adjacent end of the other plate and tapering to a slender point, said point being slightly curved outward, the adjacent end of the opposed side plate contacting closely 5 with the base of said pointed end and lying substantially flush with the inner face thereof to form a smooth unobstructed surface to facilitate the passage of the shuttle through

the work, said shuttle having thread passages at each end.

In testimony whereof I affix my signature in presence of two witnesses.

MAZEL L. PORTER.

Witnesses:

RUTH PORTER,
HERMAN O. PORTER.
